CORE DRILL

John H. Howard, Huntington Park, and William H. Maxwell, Beverly Hills, Calif., assignors to Globe Oil Tools Company, Los Nietos, Calif., a corporation of California

Application December 1, 1933, Serial No. 700,506

4 Claims. (Cl. 255—72)

This invention relates to a well drilling tool and relates more particularly to a well core drill. It is a general object of the invention to provide a practical, improved core drill embodying a positive, dependable and effective core catching and retaining means.

It is another object of the invention to provide a core drill embodying a core catching means that may be positively operated into effective holding and retaining engagement with the core without manipulating the drill or the string of pipe carrying the drill.

It is another object of the invention to provide a core drill involving a novel and particularly effective hydraulically operated core catching means.

It is another object of the invention to provide a core drill including a core catching means that does not engage the core or in any manner interfere with the core during the drilling operation and that may be controlled or governed from the upper end of the well.

It is another object of the invention to provide a core catching means that is positively operated by longitudinal movement of the inner core receiving barrel of the drill without movement of the outer barrel of the drill.

It is another object of the invention to provide a core drill including an inner barrel that is movable longitudinally in the outer barrel and means for hydraulically operating the inner barrel downwardly to positively operate the core catching means. In the drill of the present invention the weight of the inner barrel assists the hydraulic means in actuating the core catcher.

It is another object of the invention to provide a core drill including an hydraulic core catcher operating means that does not interfere with the normal flow of circulation fluid during the drilling operation.

It is another object of the invention to provide a core drill having simple, sturdy core gripping and supporting dogs that are positively forced into gripping and supporting engagement with the core by an hydraulic operating means.

It is a further object of the invention to provide a core drill of the character mentioned involving means whereby the driller is informed or made aware of the fact that the core gripping and engaging dogs have been fully actuated upon the inner barrel reaching its extreme down position.

Other objects and features of our invention will become apparent from the following detailed description of a typical form and application of

the invention throughout which description reference may be had to the accompanying drawings, in which:

Fig. 1 is a longitudinal detailed sectional view of the core drill provided by the invention illustrating the inner barrel in the latched position where the core engaging dogs are in their unactuated positions. Fig. 2 is a view similar to Fig. 1 showing the inner barrel in its down position and the dogs in their actuated positions. Figs. 3, 4 and 5 are enlarged transverse detailed sectional views taken substantially as indicated by lines 3—3, 4—4 and 5—5 respectively on Fig. 2, and Fig. 6 is a more or less diagrammatical view illustrating the drill of the present invention in operation in a well on the lower end of a drilling string.

The core drill provided by this invention includes generally an outer barrel 10 having a bit head 11 on its lower end, core gripping and supporting dogs 12, an inner barrel 13 adapted to move downwardly to actuate the dogs 12, means 14 releasably holding the inner barrel 13 against movement, and hydraulic means 15 for releasing the means 14 and for moving the inner barrel 13 downwardly to actuate the dogs 12.

The outer barrel 10 is an elongate tubular member adapted to be attached to the lower end of a string P of drill pipe, or the like. A connecting member or sub 16 is provided on the upper end of the barrel 10 to form a part thereof and to facilitate connection with the lower end of the drilling string p. The sub 16 is provided with a central longitudinal fluid passage 17 for conducting circulation fluid downwardly from the drilling string as will be more fully described. A sub 18 is provided on the lower end of the outer barrel 10 to carry the bit head 11. The sub 18 is provided at its lower end with a downwardly projecting screw threaded pin 19.

The bit head 11 is provided on the lower end of the outer barrel 10 to make an annular cut in the earth formation and leave the core C. The bit head 11 is a tubular member which may be threaded on the pin 19. In accordance with the broader aspects of the present invention, the bit head 11 may be provided with any suitable form of cutting means. In the particular case illustrated in the drawings, a plurality of downwardly and outwardly projecting cutting blades 20 is provided on the bit head 11. Each of the blades 20 may have a downwardly projecting tooth 21 at its inner end to cut or trim the core C to pass upwardly into the bit head and inner barrel. An annular groove 22 is provided in the bit head 11 at the lower end of the pin 19 and fluid

passages 23 extend downwardly from the groove 22 to discharge from the lower end of the bit head in front of the several blades 20. The central opening of the bit head is provided with two vertically spaced annular shoulders 24 and 25. The portion 26 of the bit head opening below the lower shoulder 25 may be inclined downwardly and inwardly.

The core gripping and supporting dogs 12 are positioned or mounted in the bit head 11 in positions to be actuated by the inner barrel 13 when it is moved downwardly by the hydraulic actuating means 15. There is preferably a plurality of dogs 12 provided in the bit head 11 at circumferential spaced points. In the particular form of the invention illustrated in the drawings, there are four equally spaced dogs 12 carried by blocks 28 arranged or inset in openings 29 in the wall of the bit head. In practice the blocks 28 may be welded in place. Sockets 30 are provided in the inner sides of the blocks 28 to receive the end portions of the dogs 12. The blocks 28 may be positioned so that their inner sides occur at the tapered portion 26 of the bit head opening in which case their inner sides may have the same inclination as the said portion of the opening.

Pivot pins or screws 32 extend through transverse openings in the dogs 12 to pivotally support them in the sockets 30. The screws 32 are carried in transverse openings in the bit head 11 and have their heads countersunk. The dogs 12 project inwardly from the blocks 28 and the upper and lower sides of their projecting portions converge to comparatively sharp outer edges. In practice the upper and lower sides of the dogs are flat, as illustrated in the drawings. Means are provided for normally yieldingly holding the dogs 12 in up positions where they do not interfere with the core C during the drilling operation. A notch 33 is provided in the pivoted end of each dog 12 and carries a torsional spring 34 which yieldingly urges the dog to the up or unactuated position. When the dogs are in their up positions their lower sides are substantially vertical and have clearance with the core C.

The inner barrel 13 is disposed longitudinally in the outer barrel 10 and is concentric with the outer barrel. The inner barrel 13 is spaced from the interior from the outer barrel 10 providing a longitudinal annular fluid passage 35 between the two barrels. The main section or body of the inner barrel 13 is of substantial length and in the case illustrated has comparatively thin walls. In accordance with the invention, the inner barrel 13 is supported for limited longitudinal movement relative to the outer barrel 10. A ring or collar 36 is provided on the lower end of the inner barrel 13 and is shiftably or slidably supported in the bit head 11. The collar 36 may be attached to the inner barrel in any suitable manner. In the particular construction illustrated, the collar 36 is welded on the lower end portion of the inner barrel. The exterior or periphery of the collar 36 is stepped having an upper portion 37 to operate in the bit head between the lower end of the pin 19 and the shoulder 24 and a lower portion 38 operating in the bit head opening between the shoulders 24 and 25. A bearing ring 39 may be provided on the portion 37 to engage the lower end of the pin 19. A multiplicity of circumferentially spaced ports 40 is provided in the portion 37 to pass fluid from the annular passage 35 downwardly to the groove 22 in the bit head. The lower end of the collar 36 is provided with an internal downwardly and outwardly inclined or

curved face 41 to cooperate with the dogs 12 to positively pivot the dogs downwardly and inwardly into the core C when the inner barrel 13 is moved downwardly with respect to the outer barrel. The face 41 is such that it has effective cooperation with the flat upper sides of the dogs 12.

A tubular head or guide 42 is provided on the upper end of the inner barrel 13. The lower portion of the guide 42 may fit into the inner barrel 13 and may be connected with the inner barrel by welding. The guide 42 projects upwardly from the inner barrel 13 to slidably fit into the passage 17 of the sub 16. The upper end of the guide 42 is open to receive the circulation fluid that is pumped downwardly through the drilling string P by the pump X at the upper end of the well. Lateral ports 43 are provided in the walls of the guide 42 to communicate with the annular fluid passage 35 so that the fluid may pass downwardly from the guide 42 into the passage 35. A valve seat 44 is provided in the lower portion of the passage 45 in the guide 42. The valve seat 44 may be screw threaded in the passage 45. A ball 46 is provided to cooperate with the seat 44 to prevent the downwardly flowing circulation fluid from entering the upper end of the inner barrel 13. The ball 46 is adapted to move upwardly from the seat 44 to permit fluid to be displaced from the inner barrel 13 as the core is received in the inner barrel. In the preferred construction, the inner barrel 13 is keyed or splined to the outer barrel to rotate therewith. In the embodiment of the invention being described keys or splines 47 are provided on the guide 42 to slidably cooperate with keyways 48 in the sub 16 to key the inner barrel to the outer barrel.

The means 14 for holding the inner barrel 13 in its up position is in the nature of a releasable latch means which positively retains the inner barrel 13 in a position where the dogs 12 are normally held retracted by the springs 34 and which is releasable by the hydraulic means 15 to allow the inner barrel to be moved downwardly to actuate the dogs. The means 14 is accordingly a control means governing the actuation of the core gripping and supporting dogs 12. The means 14 includes a latch 50 carried by the sub 16 for cooperating with the guide 42. A recess 51 is provided in the interior of the sub 16 to carry the latch 50. A pivot pin or screw 52 passes through the recess 51 and an opening in the latch to pivotally support the latch in the recess 51. A spiralled spring 53 surrounds the pivot screw 52 and acts on the latch 50 to normally yieldingly urge the latch outwardly to cooperate with an opening 54 in the wall of the guide 42. The nose or active portion of the latch 50 is shouldered to cooperate with the upper wall of the opening 54 in a manner to dependably hold the inner barrel 13 against downward movement during the drilling operations, etc. The latch 50 is proportioned to project into the fluid passage 45 of the guide and its projecting portion has a downwardly and inwardly inclined face 55. As the drill is run into the well and during the drilling operation, the latch 50 cooperates with the opening 54 to hold the inner barrel 13 in the position illustrated in Fig. 1 of the drawings so that the dogs 12 are retained in their up and inactive positions by the springs 34.

The hydraulic actuating means 15 is adapted to release the latch 50 and immediately thereafter force or move the inner barrel 13 downwardly to actuate the dogs 12. The means 15 includes a

valve seat 60 in the fluid passage 45 of the guide. The valve seat 60 is spaced some distance below the latch receiving opening 54. In practice the valve seat 60 may be replaceably screw threaded in the guide 42. The hydraulic means 50 includes a closure member or valve member 61 adapted to be dropped or pumped downwardly through the drill string P to release the latch 50 and to cooperate with the seat 60. The valve member 61 is preferable in the form of a ball proportioned to fairly accurately fit the passage 45 above the seat 60. The seat 60 is shaped to effectively receive the ball 61 so that the ball closes the passage 45 against the downward flow of fluid. When a sufficient or desired amount of core C has been drilled or taken the ball or closure member 61 may be introduced into the drilling string P at the upper end of the well to drop or be pumped downwardly so as to enter the upper end of the guide passage 45. The pressure on the pumped circulation fluid forces the ball 61 downwardly through the passage 45 to pivot the latch 50 outwardly and disengage it from the opening 54 and then come to rest on the seat 60 where it prevents downward flow through the passage. The fluid pressure then positively forces the released inner barrel 13 downwardly to actuate or pivot the dogs 12 inwardly into the core C to obtain a dependable gripping or supporting engagement with the core. The invention provides means for informing the driller when the dogs 12 have been fully actuated which means automatically renews or starts the circulation of fluid through the tool immediately after the actuation of the dogs. Circumferential spaced openings or ports 70 are provided in the wall of the guide 42 and are positioned so as to move into communication with the upper end of the annular passage 35 when the barrel 13 reaches its final down position. The ports 70 are closed when the inner barrel 13 is held in its up or normal position by the latch 50.

It is believed that the operation of the tool provided by the present invention will be readily apparent from the foregoing detailed description. The core drill is run into the well on the drilling string P with its parts in the positions illustrated in Fig. 1 of the drawings. The latch 50 dependably holds the inner barrel 13 in its up position, during the running of the tool into the well and during the drilling operation. During the drilling the bit head 11 makes an annular cut or bore in the formation providing the core C which is received by the inner barrel 13. Circulation fluid is pumped downwardly through the drilling string P to discharge from the ports 23 at the lower end of the bit head. The circulation fluid flows downwardly through the passage 45 of the guide 42 to enter passage 35 and then passes downwardly through the ports 40 and groove 22 to finally discharge from the ports 23. When a core C of sufficient length has been cut or obtained the rotary drilling is suspended and the ball or closure member 61 is introduced into the drilling string P at the upper end of the well. After the ball or closure member 61 has been introduced into the drilling string the circulation fluid is pumped downwardly through the string by the pump X so that the ball 61 is pumped downwardly into the upper end of the guide 42. The closure member or ball 61 forced downwardly through the passage 45 by the fluid pressure pivots the latch 50 outwardly to disengage it from the opening 54 and then comes to rest on the seat 60. The pressure of the pumped circulation fluid

then forces the freed or released inner barrel 13 downwardly so that the inclined face 41 on its lower end cooperates with the upper sides of the dogs 12 to pivot the dogs downwardly and inwardly into the core C. The dogs 12 are thus positively operated into full effective gripping and retaining engagement with the core. It is to be noted that the weight of the inner barrel 13 aids the hydraulic means in its actuation of the dogs 12. When the inner barrel 13 reaches its down position where the dogs 12 are actuated as just described, the ports 70 come into communication with the upper end of the passage 35 so that the circulation fluid is again free to flow downwardly through the tool. With the inner barrel 13 in its down position, the lower end of the passage 35 is in direct communication with the groove 22. The downward circulation of fluid is temporarily stopped when the ball 61 is on the seat 60 and the inner barrel 13 is being forced downwardly so that the pump X may labor. Upon the opening of the ports 70 to the passage 35 circulation is resumed and the pump X no longer labors, indicating to the driller that the dogs 12 have been fully actuated. After the dogs 12 have been actuated in the manner described, the drill may be raised to break the core C free from the earth formation and may then be withdrawn from the well. The dogs 12 in being positively and fully actuated by the downward movement of the inner barrel 13 obtain dependable engagement with the core C and support the core as the tool is withdrawn from the well.

Having described only a typical preferred form of our invention we do not wish to limit ourselves to the specific details set forth, but wish to reserve to ourselves any changes or variations that may appear to those skilled in the art or fall within the scope of the following claims:

Having described our invention, we claim:

1. A core drill to be operated on a string of pipe including, an outer barrel to be connected to the lower end of the string and having cutting means on its lower end for cutting a core, an inner barrel for receiving the core and having its lower portion guided in the cutting means, the inner barrel being movable longitudinally with respect to the outer barrel, a core catching dog carried by the outer barrel at the cutting means, a tubular member on the upper end of the inner barrel slideable in the outer barrel and normally conducting fluid passed downwardly through the string, a releasable latch cooperating with the tubular member to suspend the inner barrel in a position where its lower end is clear of the core catching dog, and a part adapted to be dropped through the string to release the latch and close said member against the downward flow whereby pressure applied to the fluid forces the inner barrel downwardly so that its lower end engages and actuates the core catching dog.

2. A core drill to be operated on a string of pipe including, an outer barrel to be connected to the lower end of the string, a cutting head on the lower end of the outer barrel for cutting a core, an inner barrel for receiving the core and having its lower portion guided in the head, the inner barrel being movable longitudinally with respect to the outer barrel, a core catching dog in the cutting head below the lower end of the inner barrel, a tubular element on the upper end of the inner barrel slideable in the outer barrel and normally conducting the fluid pumped downwardly through the string, a latch releasably en-

gaging the element to hold the inner barrel in a position where its lower end is spaced above the dog, a valve seat in the tubular element, and a member adapted to be introduced into the string 5 to be pumped downwardly through the tubular element to release the latch and then cooperate with the seat to close the element against downward flow whereby the inner barrel may be moved downwardly by fluid pressure so that its lower 10 end engages and actuates the dog.

3. A core drill including an outer barrel adapted to be attached to a tubular operating string, a bit head on the lower end of the outer barrel for cutting a core, a core catching dog pivoted in 15 the bit head, an inner barrel for receiving the core and having its lower portion guided in the head, the lower end of the inner barrel being normally spaced above the dog and being operable to actuate the dog, and fluid pressure actuated means 20 for moving the inner barrel downwardly to actuate the dog.

4. A core drill to be operated on a string of pipe including, an outer barrel to be connected to the lower end of the string, a cutting head on the

lower end of the outer barrel for cutting a core, an inner barrel for receiving the core and having its lower end guided in the head, the inner barrel being movable longitudinally with respect to the outer barrel, a core catching dog in the head below the lower end of the inner barrel, a tubular element on the upper end of the inner barrel slideable in the outer barrel and normally conducting the fluid pumped downwardly through the string, a latch releasably engaging the element to hold the inner barrel in a position where its lower end is spaced above the dog, a valve seat in the tubular element, and a member adapted to be introduced into the string to be pumped downwardly through the tubular element to release 15 the latch and then cooperate with the seat to close the element against downward flow whereby the inner barrel may be moved downwardly by fluid pressure so that its lower end engages and actuates the dog, there being a port in the element 20 opened to pass fluid downwardly through the drill upon the inner barrel reaching its down position.

JOHN H. HOWARD.

WILLIAM H. MAXWELL.
